Samuel Morgan, of South Norwalk, Conn.
Assignor to
Himself and Chauncy Adams.
Letters Patent No 1262, dated June 19, 1860

The schedule referred to in these Letters Patent and making part of the same.

22

Dec 1262

To all whom it may concern:

Be it Known that I, Lemuel Morgan, of South Newark, Com-
munity of Fairfield and State of Connecticut, have invented or produced a new and original
Pattern or design for Fire Shovel, and I do hereby declare that the following is a
full and exact description of the same: and referring to the accompanying Photograph
is Views, in which the same letters indicate like parts in each of the figures -

In the accompanying Photographic Views -

Fig: 1. Shows a front elevation of my new pattern or
Design for fire Shovel, &c. and

Fig: 2. Shows a back side view of the same.

a. is a flat bottom configurated with a curved, slant-
ed end b, flat slanted sides c, and a beaded handle socket d, combined to con-
stitute a plain and tasteful Pattern or design for a fire coal or ash shovel.

I claim the form and configuration of a Pattern or Design
for fire, Coal or ash shovel as described and represented.
